UNITED STATES PATENT OFFICE.

WILLIAM DUBILIER AND PHILIP DUBILIER, OF NEW YORK, N. Y.

ELECTRICAL-DISCHARGE-PRODUCING DEVICE.

1,307,854.

Specification of Letters Patent. Patented June 24, 1919.

Application filed August 15, 1916. Serial No. 115,105.

To all whom it may concern:

Be it known that we, WILLIAM DUBILIER and PHILIP DUBILIER, of New York city, in the county of New York, and in the State 5 of New York, have invented a certain new and useful Improvement in Electrical-Discharge-Producing Devices; and do hereby declare that the following is a full, clear, and exact description thereof.

10 The object of our invention has been to produce electrical discharges and to provide an apparatus therefor, by which arcs possessing a relatively high degree of heat can be produced, for such purposes as explosive 15 engines, lamps, cigar lighters, or other form of apparatus, in which an electric flow or discharge is desired across a resistance that is high relative to the source of supply, so that a discharge of comparatively large 20 volume, and therefore of good heating capacity is produced, and to such ends our invention consists in the apparatus hereinafter specified.

In the accompanying drawing, the figure 25 is a diagrammatic representation of one embodiment of our invention.

While we have illustrated our invention by the best embodiment known to us, such embodiment is to be regarded as typical 30 only of many possible embodiments, and our invention is not to be confined thereto.

In the illustrated embodiment, the source of current 1 is connected in an initial primary circuit containing key 3, an electro-magnetic vibrator, and a primary winding 35 8 of a transformer. The vibrator or interrupter consists of a magnetic core 4 inclosed by a coil 2, which coil is connected to a terminal 7 by means of the wire 4^a. Movable 40 contact 5 of the interrupter is attached to terminal 7 by means of spring 5^a which is biased to hold contact 5 normally against fixed contact 6. The wire 6^a connects fixed 45 contact 6 in circuit with primary winding 8 of a transformer, and a return wire 9 leads back to the source of current 1.

A secondary winding 13 of the transformer is connected in a secondary circuit containing a gap formed by electrodes 14—50 15, and such secondary circuit is completed by the wire 16 leading from electrode 15 to a point in the primary circuit intermediate coil 2 and fixed contact 6.

The action of the interrupter in inducing 55 a current in the secondary circuit is supplemented by an oscillating circuit containing

the interrupter and the transformer primary 8, which oscillating circuit includes a condenser 10, one side of which is connected to terminal block 7 by wire 11, and the other 60 side to return wire 9 by wire 12.

In the operation of the device when key 3 is closed the primary current will pass from source of energy 1 through coil 2, wire 4^a, terminal 7, spring 5^a, contacts 5 and 6, wire 6^a, primary winding 8, and return wire 9. The core 4 will then attract movable contact 5, breaking the primary circuit, whereby, through the action of primary coil 8, a secondary current will be induced in the secondary winding 13. The action of the primary coil 8 is supplemented by oscillations produced in oscillating circuit 10, 11, 7, 5^a, 5, 6, 6^a, 8, 9, 12, and the resultant effect upon coil 13 is sufficient to break down the gap 75 14—15, and render the same conductive. The primary voltage from source 1 is then sufficient to establish a primary current across gap 14—15 through a circuit including key 3, coil 2, wire 16, electrodes 14—15, 80 secondary winding 13, and return wire 9. The flow of current through coil 2 energizes coil 4, thus holding open the original primary circuit at the contacts 5 and 6, cutting the transformer and oscillating circuit out 85 of action, so long as the primary current is established across the gap 14—15. In case such primary current for any reason ceases, the original primary circuit will again be completed at contacts 5 and 6, and the action 90 of the transformer and oscillating circuit in rendering the gap 14—15 conductive will be repeated.

When the high potential discharge flows across the gap 14, 15, if there is a medium 95 across said gap such as gases of an explosive engine, or the end of a cigar, a gas filled gap, or any other conductive medium, whose conductivity can be raised by the action of the high potential discharge, then the action 100 just described, will take place and an arc will be formed following the oscillating high potential discharge and we find that the temperature of the said arc, or whatever the form of primary current flowing across the 105 gap may be termed, is such, owing to the increase in volume and temperature as compared with the high potential discharge, that the gases of the engine will be lighted with much more certainty than the usual 110 sparking mechanism, or the cigar will be readily lighted, or an illuminating arc can

be formed, so that very advantageous results are obtained.

The interrupter or condenser-discharging device acts as a relay in effect, first aiding 5 in forming a low resistance path for the primary current and then automatically cutting out the secondary circuit, so long as the arc is maintained, and automatically restoring the high potential discharge when 10 the arc or other form of primary current is interrupted. When too much resistance is inserted in the gap 14, 15 for the primary current to overcome, the condenser-charging device is automatically set in operation 15 again endeavoring to reduce the resistance of the gap sufficiently to permit the flow of the primary current. When, however, the conductivity of the gap is sufficient so that the primary current can flow across, the condenser-charging device is maintained inoperative and cuts out the secondary circuit. Any kind of current interrupter or condenser-charging device can be used and the same result obtained. It is preferable that 25 the condenser 10 should not be of such capacity as to extinguish the arc.

We claim:

1. The combination with an induction coil system having an air gap in the secondary 30 circuit, of means for interrupting the primary circuit to bridge said gap with the secondary current, means whereby the primary current flows across the gap when the same has been bridged by the secondary current, 35 and means whereby the flow of primary current across the gap holds open the initial primary circuit.

2. A discharge producing device comprising 40 a primary circuit containing a transformer primary and an electromagnetic circuit interrupter, a secondary circuit containing a gap and a transformer secondary, said secondary circuit being connected to the primary circuit between the interrupter coil and 45 contacts.

3. A discharge producing device comprising 50 a primary circuit containing a transformer primary and an electromagnetic circuit interrupter, a secondary circuit containing a gap and a transformer secondary, and means whereby the primary current may be established through said gap when the same has been bridged by the secondary current.

4. A discharge producing device comprising 55 a primary circuit containing a transformer primary and an electromagnetic circuit interrupter, an oscillating circuit consisting of a condenser, said primary and interrupter, a secondary circuit containing a 60 gap and a transformer secondary, said secondary circuit being connected to the primary circuit between the interrupted coil and contacts.

5. A discharge producing device comprising 65 a primary circuit containing a trans-

former primary and an electromagnetic circuit interrupter, an oscillating circuit consisting of a condenser, said primary and interrupter, a secondary circuit containing a gap and a transformer secondary, and means whereby the primary current may be established through said gap when the same has been bridged by the secondary current. 70

6. The combination with an induction coil system having an air gap in the secondary 75 circuit, of an interrupter located in the primary circuit, means for opening said interrupter to induce a current in the secondary circuit which will bridge said gap, means whereby the primary current will be directed 80 across said gap, and means whereby the interrupter will be held open so long as the primary current flows across the gap.

7. A discharge producing device comprising 85 a primary circuit containing an electromagnetic interrupter and a transformer primary, an oscillating circuit including the transformer primary, a secondary circuit containing a gap and a transformer secondary, and means whereby the primary current 90 may be established through said gap when the same has been bridged by the secondary current, and the secondary circuit and oscillating circuit cut out.

8. The combination with an induction coil 95 system having a gap in the secondary circuit, of means whereby the initial primary circuit is held open and the primary current directed across such gap, when the gap is bridged by the secondary current and the 100 secondary current reestablished whenever the flow of current across the gap ceases.

9. The combination with an induction coil system having an air gap in the secondary 105 circuit, of an interrupter located in the primary circuit, means whereby the primary current will be broken in the primary circuit and directed across the gap when the gap has been bridged by the secondary current, and said primary circuit held open so long 110 as the primary current is maintained across the gap, said means automatically reestablishing the primary circuit to again break down the gap, in case the flow of primary current across the gap ceases. 115

10. The combination with an induction coil system having an air gap in the secondary circuit, of an electromagnetic interrupter having a separate actuating coil located in the primary circuit, one electrode of said gap 120 being connected in the primary circuit between the interrupter coil and contacts.

11. The combination with an induction coil system having an air gap in the secondary circuit, of an electromagnetic interrupter 125 having a separate actuating coil located in the primary circuit, one electrode of said gap being connected in the primary circuit between the interrupter coil and contacts, and a condenser adapted to produce oscilla- 130

tions in the primary of the induction coil, upon opening of the interrupter.

12. The combination with an induction coil system having an air gap in the secondary circuit, of an interrupter located in the primary circuit, a condenser adapted to produce oscillations in the primary of the induction coil upon opening of said interrupter, means whereby the primary current will be broken in the primary circuit and directed across the gap when the gap has

been bridged by the secondary current, and said primary circuit held open so long as the primary current is maintained across the gap, and means for automatically reestablishing the primary circuit to again break down the gap, in case the flow of primary current across the gap ceases. 15

In testimony that we claim the foregoing we have hereunto set our hands.

WILLIAM DUBILIER.
PHILIP DUBILIER.
